UNITED STATES PATENT OFFICE.

FELIX E. LIETZ, OF BUFFALO, NEW YORK.

SHINGLE.

Application filed November 19, 1924. Serial No. 750,955.

To all whom it may concern:

Be it known that I, FELIX E. LIETZ, a citizen of the United States, residing at Buffalo, in the county of Erie and State of New York, have invented new and useful Improvements in Shingles, of which the following is a specification.

This invention relates more particularly to the class of shingles which are laid diagonally and provided with flaps or turned-under corners which thicken the straight lower edges of the shingles and give them a strong and heavy appearance. These shingles are usually composed of prepared or composition roofing such as felt saturated with asphalt and faced with crushed slate or other similar mineral.

One of the objects of my invention is to improve the means for locking the thickened lower corners of such shingles in place, so that they will effectually withstand the lifting action of high winds and driving rainstorms.

A further object is the provision of a shingle-locking device which is concealed in all positions or adjustments of the shingles, producing a sightly roof.

In the accompanying drawings:

Figure 1 is a fragmentary top plan view of a roofing embodying the invention. Figure 2 is a fragmentary bottom plan view thereof. Figure 3 is a vertical cross section on line 3—3, Fig. 2. Figure 4 is a fragmentary perspective view of the invention. Figure 5 is a view similar to Fig. 2, showing a modified construction of the improvement. Figure 6 is a vertical cross-section on line 6—6, Fig. 5.

Similar characters of references indicate corresponding parts throughout the several views.

10 indicates the usual roof boards or sheathing, and 11 the customary starting strip of roofing material laid along the margin of the roof.

12 indicates the shingles, preferably constructed of roofing material of the character above described and laid diagonally in the customary overlying courses, with the side corners of the adjacent shingles partly cut away and abutting against each other, as shown in the drawings. The shingles are preferably lapped three and a quarter inches to obtain better protection against leaks, but they may be lapped a different width, if desired.

The lower corner of each shingle has a straight or horizontal edge 13 and is provided on its underside with a flap 14 of substantially the same thickness as the body 60 of the shingle, so that said corner is made up of a double thickness of material which gives its lower edge a strong and heavy appearance. This flap or extra corner layer may be produced by cutting the shingle of substantially square form and turning or bending its lower corner under the body of the shingle, as shown in Figs. 2, 3 and 4; or by cutting the lower corner of the shingle-blank off on a horizontal line and securing to its back a separate piece of roofing material 14^a, as shown in Figs. 5 and 6, this back layer corresponding in shape to the flap 14. Rivets 15 or other suitable fastenings may be used for this purpose. 75 The flap 14 or 14^a is adapted to fit into the V-shaped space formed between the upwardly-converging edges of the two underlying shingles, as shown in Figs. 2 and 4.

Referring to the embodiment of the invention illustrated in Figs. 1, 2, 3 and 4, the flap 14 carries an upright locking tongue or member 16 which extends upwardly beyond the free end of the flap and is adapted to be inserted under the adjacent 80 side corners of a pair of underlying shingles between their usual fastening nails 17, as shown. This tongue is constructed of comparatively strong and stiff material such as galvanized iron of comparatively heavy 85 gage, in order not to buckle in inserting it and so as to firmly lock the butt or thickened lower end of the shingle down in place without the use of nails or similar fastenings other than the nails 17. At the 90 same time, the locking tongue is so thin in comparison with the thickness of the shingle-body, that it can be easily thrust under the side corners of the underlying shingles without the necessity of lifting or displacing them, which act tends to loosen the 95 joint.

By arranging the locking tongue or member lengthwise or vertically of the corner flap of the shingle, it may without objection 100 be extended upwardly beyond the flap to a sufficient length to insure a strong and reliable lock.

This upright arrangement of the tongue affords the further important advantage that 110 it always remains hidden from view regardless of whether the corner flap of the cor-

responding shingle is fitted closely against the side edges of the adjacent shingles or whether that shingle is lowered more or less out of that position to secure proper alignment of the shingles of each course, the tongue not showing through the resulting gaps because it does not extend beyond the side edges of the flap or the shingle body. This arrangement of the tongue wholly within the bounds of the shingle also guards against bending or breakage of the tongue in handling and shipment, which is liable to occur when the locking device extends beyond the edges of the shingle. The rivets or fastenings which secure the tongue to the corner flap 14 do not pass through the shingle-body and are not exposed on the face of the shingle. The roof is therefore free from unsightly rivet-heads or similar fastenings, and the shingles are not liable to become unlocked and leaky, as is the case where such fastenings extend through the shingles and are eventually stripped therefrom by the lifting action of winds under their lower corners.

This central vertical position of the locking tongue is also advantageous in that in fitting the shingles to the ends and valleys of a roof, they may be cut off on one side of the tongue, avoiding the necessity of removing the tongue or cutting through it.

The tongue is preferably secured to the back of the flap or that side facing the back of the shingle, as shown in Figs. 1, 2, 3 and 4, but if desired, it may be applied to the face of the flap as shown at 16* in Figs. 5

and 6. In either case, the tongue may be secured to the flap by rivets 18 or other appropriate fastenings.

I claim as my invention:

1. A shingle having a corner-flap on its underside and a locking tongue stiffer than said flap carried by the same, said tongue extending lengthwise of said flap and beyond its free edge.

2. A shingle composed of composition roofing and having a thickening flap on the underside of its lower corner, and a locking tongue of stiff material carried by said flap and extending upwardly beyond its free edge and adapted to pass under the side edges of underlying shingles.

3. A shingle composed of composition roofing and having a flap on the underside of its lower corner, said flap being of substantially the same thickness as the shingle-body, and a relatively stiff locking tongue thinner than said flap carried by the same, said tongue extending upwardly beyond said flap and adapted to pass under the side edges of underlying shingles.

4. A shingle composed of composition roofing and having a thickening flap on the underside of its lower corner, and a relatively thin locking tongue of stiff material applied to said flap on the side facing the back of the shingle, said tongue being arranged centrally and vertically of the flap and extending upwardly beyond its free edge.

FELIX E. LIETZ.
